UNITED STATES PATENT OFFICE.

NEWTON FELLABAUM, OF SPERRY, OKLAHOMA.

DOUBLE-ACTING OIL AND WATER PUMP.

Application filed May 29, 1922. Serial No. 564,546.

To all whom it may concern:

Be it known that I, NEWTON FELLABAUM, a citizen of the United States, residing at Sperry, in the county of Tulsa and State of Oklahoma, have invented certain new and useful Improvements in Double-Acting Oil and Water Pumps; and I do declare the following to be a full, clear, and exact description of the invention, such as will enable others skilled in the art to which it appertains to make and use the same.

This invention relates to an improved double acting pump for use principally in connection with oil wells and one object of the invention is to provide a pump having an improved arrangement of casing construction and also having an improved multiple standing valve in its lower portion and upper and lower working valves connected 20 in an improved manner.

Another object of the invention is to provide an improved base carrying the standing valve and having inner and outer pipes leading therefrom, the inner pipe having the lower working valve reciprocating therein and the base being so constructed that oil entering its lower end may be divided and part of it pass through the valve controlled lower portion of the standing valve and up 30 into the outer pipe of the lower casing section and the remaining portion pass through the valve controlled upper portion of the standing valve into the inner pipe of the lower casing section in which the lower working 35 valve moves.

Another object of the invention is to provide an improved type of connection between the lower casing section and the upper casing section, the means for connecting the 40 two casing sections including inner and outer sleeves communicating with the inner and outer pipes of the casing sections, the pump rod being passed into the upper casing section and connected with the upper 45 working valve and the upper and lower working valves being connected by a connecting rod passing through the inner tube of the device connecting the upper and lower casing sections.

50 Another object of the invention is to provide improved means for preventing flow of oil through the inner tube of the coupling section and to further provide improved means for anchoring packing and bushing

elements within the inner sleeve of the coupling section. 55

Another object of the invention is to provide improved means for releasing securing latches and permitting withdrawal of the working valves and packing and bushing 60 means when so desired.

Another object of the invention is to so construct this double acting pump that the oil when leaving the base may pass partially through the inner pipe of the lower casing 65 section and partially through the outer pipe thereof, the oil in the inner pipe of the lower casing section then passing into the outer pipe of the coupling section to mix with oil passing into the outer pipe of this coupling 70 section from the outer pipe of the lower casing section and the oil passing upwardly through the coupling section and a portion of it passing directly into the outer pipe of the upper casing section and through the 75 head of the pump into the well casing or stand pipe and the remainder passing into the inner pipe of the upper casing section in which the upper working valve moves.

Another object of the invention is to so 80 construct this pump that the parts thereof may be readily assembled or taken apart.

This invention is illustrated in the accompanying drawings, wherein:

Figures 1 and 1' show the improved pump 85 in vertical section.

Figure 2 is an enlarged sectional view of the coupling section and adjacent portions of the upper and lower casing sections with the latch of the packing means released and the 90 pumping means ready for withdrawal.

Figure 3 is an enlarged sectional view of the upper casing section with the upper working valve shown in section.

This improved oil pump is provided with 95 a base portion 1 having an inlet nozzle in the form of a pipe 2, a head 3 carried by a stand pipe 4 through which the oil passes to the surface of the ground, upper and lower casing sections indicated in general 100 by the numerals 5 and 6, and an intermediate coupling section which is indicated in general by the numeral 7 and serves to connect the upper and lower casing sections 5 and 6. The base 1 is formed as a casting 105 and is provided with a central passage or pocket 8 in which is seated a standing valve 9 which is of a multiple construction and

provided with a valve cage 10 at its upper end and a second valve cage intermediate its length. Passes 12 and 13 are formed in this base 1, the passage 12 extending from the 5 lower end of the base and communicating with the pocket 8 intermediate its length so that oil passing through this passage 12 may enter the standing valve intermediate its length and pass upwardly to the 10 valve cage 10. The passage 13 has its lower end communicating with the pocket 8 in operative relation to the lower valve cage 11 so that oil passing upwardly through the lower end portion of this multiple standing 15 valve 9 may pass into the lower end of the passage and upwardly through the same. The lower casing section is provided with inner and outer tubes or pipe sections 14 and 15, the inner tube 14 being screwed into a nipple 16 formed in the upper end portion of the base 1 and the outer tube 15 being screwed into a pocket in the upper end portion of the base and positioned in spaced relation to the nipple 16 into which the tube 14 is 20 mounted. It will thus be seen that oil passing through the upper portion of the standing valve may pass into the inner tube 14 of the lower casing section and that oil passing through the lower portion of the 25 standing valve may pass upwardly through the passage 13 and into the outer tube 15 of this lower casing section. The upper casing section is provided with inner and outer tubes 17 and 18 which correspond to 30 the tubes 14 and 15 of the lower casing section and have their upper ends connected with the head 3, the inner tube 17 being screwed into a threaded socket 19 of the cap 3 and the outer tube having its upper 35 end screwed into an annular seat or pocket 20 formed in the lower face of this head. Above the sleeve 19 into which the inner tube 17 is screwed, the head or cap 3 is hollow and about the sleeve the head has been 40 provided with either a plurality of oil passages or a single oil passage extending about the sleeve for the major portion of its circumference. It will thus be seen that oil passing upwardly through the inner and 45 outer tubes of the upper casing section can pass into the head 3 and from the head pass into the stand pipe or tube 4 through which it will pass upwardly to a point above the ground. 50 The intermediate or coupling section which connects the upper and lower casing sections is provided with an outer tube 21 and an inner tube 22 which is provided at its upper and lower ends with heads 23 and 55 24 which fit snugly within the upper and lower end portions of the outer tube 21. The upper head or filler 23 is provided with a central passage 25 which forms a continuation of the interior of the inner tube 22 and has its upper end portion internally 60 threaded so that the lower end of the inner tube 17 of the upper casing section may be screwed into the upper head or filler. The inner portion 26 of this head extends in spaced relation to the outer walls of the 65 heads of the major portion of the circumference thereof thus providing an oil passage 27 and the upper end portion of this head is internally threaded as shown clearly in Fig. 2 so that the lower end of the outer tube 18 of the upper casing section may be screwed into the upper end portion of this head. Therefore, oil passing upwardly through the outer tube 7 of the coupling section may pass through the oil passage 70 27 and into the lower end portion of the outer tube of the upper casing section. At one side, the central portion 26 of this upper head is solid with the outer portion and in this portion, there has been provided a 75 passage 28 so that oil might pass upwardly through this passage and through the upper end thereof into the passage 25 and then up into the inner tube 17 of the upper casing section. It will thus be seen that oil 80 passing upwardly through the coupling section may be divided and a portion of the oil pass up into the inner tube of the upper casing section and the remainder up into the outer tube of the upper casing section. 85 At its lower end, the inner tube 22 has its head 24 provided with an extended annular wall portion 29 which is internally threaded to receive the threaded upper end portion of the outer tube 15 of the lower casing section, a passage 30 is formed in this head 24 so that oil passing upwardly from the tube 15 may pass through this passage 30 into the outer tube 7 of the coupling section. 90 The head 24 is provided with a central passage which is threaded so that the upper end portion of the tube 14 of the lower casing section which extends above the upper end of the tube 15 may be screwed into the threaded central opening of the head 24. 95 Adjacent this head 24, the tube 22 is provided with a passage 31 communicating with the interior of the outer tube 21 so that oil passing upwardly through the tube 14 100 may pass into the outer tube 21 of the coupling section and mingle with the oil passing into this tube through the passage 30. It will thus be seen that the oil which passes upwardly through the lower casing section 105 through the inner and outer tubes thereof will be brought together in the coupling section and will then be again separated and a portion of it passed upwardly through the inner tube of the upper casing section and the remainder pass upwardly through the outer tube of the upper casing section. 110 The pump rod 32 extends down through the stand pipe 4 into the inner tube 17 of the upper casing section and has its lower end 115 provided with a coupling head 23 which en- 120 125 130

gages with a cage 34 having the usual valve balls 35 positioned therein. This valve cage 34 is of the usual construction provided in connection with working valves of an oil pump and is connected with the usual hollow stem 36 which carries the bucket 37 and has its lower end connected with a cage 38. A connecting rod 39 extends from this lower cage 38 through the inner tube 22 of the coupling section and down into the inner tube 14 of the lower casing section and has its lower end connected with the valve cage of the lower working valve. This working valve is indicated in general by the numeral 10 40 and is not described in detail as it will be a duplicate of the upper working valve. The similarity of construction can be readily seen by comparing the upper working valve shown in detail in Fig. 3 with the portion of 15 the lower working valve shown in detail in Fig. 2. In order to prevent passage of oil through the inner tube 22 of the coupling section between the side ports 32 and upper end of the oil passage 28, there has been 20 provided packing means including the sleeve 41 which fits within the tube 22 about the connecting rod 39 and has its upper end closed by a packing nut 42 which engages a washer 43 and will move this washer to 25 compress a spring 44 thus placing the spring under tension so that the washer 45 beneath the spring will be moved to compress the packing material 46 about the connecting rod 39. Beneath the sleeve 41 and connected 30 therewith, there has been provided a packing element indicated in general by the numeral 47 and including oppositely extending cups 48 and 49 to prevent oil from passing through the inner tube 22 below the sleeve 35 41, the cup 48 preventing the oil from passing downwardly in this inner tube and the cup 49 preventing the oil from passing upwardly through the tube. Below the cup 49 is a tubular extension 50 which fits upon 40 the connecting rod 39 and at its lower end is provided with upwardly extending spring latch arms 51 which are provided with longitudinally curved shoulders 52 and hook-shaped end portions 53. These latch- 45 arms 51 normally extend in diverging relation to the tube 50 so that when the working valves are passed downwardly through the pipe 4 into the upper and lower casing sections, the hooked end portions 53 of the latches may move into the seats 54 and thus serve to anchor the packing means in the inner tube of the coupling sections. The coupling 55 which connects the lower end of the connecting rod 39 with the lower 50 working valve 40 is in the form of a cup having oil passages 56 in its lower portion and having its walls provided with an annular seat 57 to receive the shoulders 52 of the latch arms. From an inspection of 55 Fig. 2, it will be seen that when the pump rod is drawn upwardly to withdraw the working valve, the arms 51 will be engaged by the walls of the coupling cup and moved to the inoperative position where they will be held when the shoulders are positioned in 70 the seats. The working valves can thus be readily withdrawn and will be retained in the inoperative position until the cup has been moved to release the latch arms. 75 When this pump is in operation and set up, the standing valve is mounted in the base and the upper and lower working valves are positioned in the upper and lower casing sections and connected by the connecting rod, the packing for the connecting rod being anchored in the inner tube of the coupling section. As the pump rod reciprocates, the oil is sucked past the upper and lower valve members of the standing valve 80 9 into the inner and outer tubes of the lower casing section and passes upwardly into the coupling section, the oil in the inner tube of the lower casing section passing through the oil passage 32 into the outer tube of the coupling section. This oil passes up through the inner tube of the coupling section and as previously explained is then divided, a portion passing into the outer tube of the upper casing section and the remainder being 85 sucked into the inner tube of the upper casing section by the upper working valve. The oil from the inner tube of the upper casing section is forced up through the head 3 into the pipe 4 and this oil will serve to 90 form a suction which will assist in drawing the oil upwardly through the outer tube of the upper casing section. It will thus be seen that the oil will be forced upwardly through the upper and lower casing sections and coupling section by a double pump action and that the oil will therefore be pumped in a very effective manner. It will be further noted that if for any reason one of the working valves should become 95 clogged, the other will remain in operation and thus permit the well to remain in operation until it can be conveniently shut down and cleaning or repairing done. When it is desired to perform the cleaning, the pump shaft is drawn upwardly and carries with it 100 the working valves. As the connecting rod 39 is drawn upwardly, the cup 55 engages the latching arms and moves them to a releasing position so that the entire structure can be bodily withdrawn from the well. 105 The working valves can then be thoroughly cleaned and replaced. After the necessary cleaning and repairing has been performed and the device is again lowered into the well, the packing having been previously moved out of position for engagement of the spring latch arms by the cup, these latch arms will engage the walls of the inner tube until the hooked end portions enter the seat 110 54. This will cause the packing to be firmly 115 120 125 130

held in the inner tube of the coupling section. If it is necessary to remove the clamping valve in order to clean or repair it, the working valves and pump rod will be removed from the well and the standing valve can be removed with the usual extracting device, and then repaired and replaced.

I claim:

1. A pump structure including upper and lower casing sections, a coupling section connecting said casing sections, working valves in said casing sections, a connecting rod connecting said valves and extending through said coupling section, a stuffing box about said rod positioned in said coupling section, anchoring means normally retaining said stuffing box in said coupling section, and means for moving said anchoring means to an inoperative position and permitting removal of the working valves and connecting rod and stuffing box.
2. The structure of claim 1 having the coupling section provided internally with a seat for receiving said anchoring means.
3. The structure of claim 1 having the coupling section provided internally with a seat for receiving the anchoring means, the anchoring means being formed of resilient material and normally extending for fitting into said seat and the means for moving the anchoring means to an inoperative position being mounted beneath the stuffing box and moving into engagement with the anchoring means to move the anchoring means to an inoperative position when the working

valves and connecting rod have been moved upwardly beyond their normal working strokes.

4. The structure of claim 1 having the coupling section provided internally with an annular recess forming a seat, the anchoring means being in the form of resilient arms carried by the stuffing box and extending from the stuffing box for fitting into said seat, the means for moving said anchoring means to an inoperative position being carried by the lower end portion of the coupling rod and engaging the arms to move the same out of said seat when the working valves and rod are moved upwardly beyond their normal strokes.

5. The structure of claim 1 having the coupling section provided internally with a seat, the anchoring means being in the form of resilient arms extending upwardly in diverging relation to the stuffing box and provided at their ends with lugs for fitting into said seat, the means for moving the anchoring means to an inoperative position consisting of a sleeve carried by the lower end portion of the coupling rod and open at its upper end whereby the sleeve may move upwardly about said resilient arms and move the arms to an inoperative position when the working valves and connecting rod are moved upwardly beyond their normal strokes.

In testimony whereof I have hereunto set my hand.

NEWTON FELLABAUM.
